ASH TRAY

James A. McAdams, 16 E. Southington,
Worthington, Ohio

Filed Aug. 14, 1961, Ser. No. 66,343

Term of patent 14 years

(Cl. D85—2)

FIG. 1

FIG. 2

FIG. 3

I claim:

The ornamental design for an ash tray as shown.
